(57) **CLAIM**

The ornamental design for a tap handle, as shown.

DESCRIPTION

FIG. 1 is a front view of the tap handle of the present invention.

FIG. 2 is a rear view of the tap handle of the present invention.

FIG. 3 is a left side view of the tap handle of the present invention and illustrates, among other things, the unique curving incline that forms the top surface of the handle.

FIG. 4 is a right side view of the tap handle of the present invention and illustrates, among other things, the unique curving incline that forms the top surface of the handle.

FIG. 5 is top view of the tap handle of the present invention; and,

FIG. 6 is a bottom view of the tap handle of the present invention.

The content represented by and/or positioned withing broken lines in FIGS. 1–6 is for illustrative purposes only and forms no part of the invention.
